UNITED STATES PATENT OFFICE.

CHARLES C. BONNEY, OF CHICAGO, ILLINOIS.

DESIGN FOR A MEDAL.

SPECIFICATION forming part of Design No. 22,455, dated May 23, 1893.

Application filed April 25, 1893. Serial No. 471,729. Term of patent 7 years.

To all whom it may concern:

Be it known that I, CHARLES C. BONNEY, a citizen of the United States, residing at Chicago, in the county of Cook and State of Illinois, have invented and produced a new and original Design for Medals, which is fully set forth in the following specification, reference being had to the accompanying drawings, in which—

10 Figure 1, represents the obverse of the medal, and Fig. 2, the reverse of the same. Fig. 3 shows a cross section on lines $x-x$ of Figs. 1 and 2.

15 The leading or characteristic features of my design consist of an obverse having a rep-

resentation of the Western Hemisphere and a reverse of the Eastern Hemisphere, and about each hemisphere an annular space. Upon this space may be placed any suitable inscription, such as: The World's Congress ²⁰ Auxiliary of the World's Columbian Exposition.

I claim—

A design for medals, substantially as shown and described.

CHARLES C. BONNEY.
